TOOL CHEST

Abe H. Oliver, Azusa, Calif.

Application April 6, 1950, Serial No. 154,271

3 Claims. (Cl. 206—16)

1

This invention relates to a tool chest and it is primarily an object of the invention to provide a chest of this kind constructed in a manner whereby a quick and easy opening of the same may be accomplished and wherein the construction is such as to give ready access to the various tools or other articles within the chest.

Another object of the invention is to provide a chest of this kind including a body member having side doors swinging outwardly and downwardly to facilitate access within the body member together with means for effectively locking said side doors in closed position.

A still further object of the invention is to provide a chest including a top drawer supporting a slideable locking bar providing means whereby outwardly swinging side doors may be held closed.

The invention consists in the details of construction and in the combination and arrangement of the several parts of my improved tool chest whereby certain advantages are attained, as will be hereinafter more fully set forth.

In order that my invention may be better understood, I will now proceed to describe the same with reference to the accompanying drawings, wherein:

Figure 1 is a view in side elevation of a tool chest constructed in accordance with an embodiment of the invention;

Figure 2 is a view in end elevation, with a portion broken away of the chest as illustrated in Figure 1;

Figure 3 is an enlarged detail sectional view taken substantially on the line 3—3 of Figure 1;

Figure 4 is an enlarged detail sectional view taken substantially on the line 4—4 of Figure 1;

Figure 5 is a fragmentary horizontal sectional view taken substantially on the line 5—5 of Figure 3;

Figure 6 is a fragmentary view partly in top plan and partly in section showing the locking bar in releasing position;

Figure 7 is a fragmentary vertical section taken lengthwise through the upper portion of the chest, with portions in elevation;

Figure 8 is a fragmentary detail sectional view taken substantially on the line 8—8 of Figure 3;

Figure 9 is a fragmentary view in side elevation of the upper central portion of the chest; and

Figure 10 is a fragmentary view in elevation of the side of the chest opposite to the portion illustrated in Figure 9.

In the embodiment of the invention as illustrated in the accompanying drawings, B denotes

2

the body of desired dimensions having a bottom wall 1, end walls 2, and the relatively low side walls 3, the major portions of the sides being normally open from the walls 2 to the open top of the body B. Substantially midway of the sides of the body B is a partition plate 4 extending from one end wall 2 to the other and also extending from the bottom wall 1 in perpendicular relation thereto, to a desired distance above the open or top end of the body B. This plate 4 is securely attached to the end walls 2 or otherwise rigidly maintained in applied position. The upper or outer margin of the plate 4 at the central portion thereof is provided with an outstanding rigid hand hold 5.

The walls 1 and 2 and the partition wall 3 are preferably of sheet metal of requisite gauge and weight.

Hingedly connected, as at 6, to the upper or free longitudinal marginal portion of each of the low side walls 3, is a closure member or plate 7 which, when in closed position, contacts the adjacent side edge portions of the end walls 2 and which side walls 3 are overlapped by the inwardly disposed flanges.

The inner faces of the closure members or plates 7 and the opposed faces of the partition plate 4 have mounted thereon at selected locations, suitable brackets 9 or the like for holding various tools or implements as may be required by the artisan or mechanic.

Snugly fitting between the upper portions of the end walls 2 at opposite sides of the partition wall 4, are the trays T of desired depth for holding such articles as accessories deemed necessary by the artisan or mechanic. Each of the trays T is of a width to extend from the partition plate 4 to an outer side margin of the end plates 2 and the tops thereof and in the present embodiment of the invention, each of the trays T is held in place, by welding, as at 10, the inner side flange 11 of the tray which is in close contact with a face of the partition plate 4.

The outer side walls 12 of the trays T extend a material distance outwardly beyond the end walls 2 of the body B as do the end walls 14. Each end wall 14 is common to the adjacent ends of both trays T. Each end wall 14 has its top edge disposed from the opposite ends disposed upwardly and inwardly to a relatively large central recess 15.

Interposed between the central top portions of the end walls 14 and in alignment with the recesses 15 and of substantially the same configuration and dimensions in cross section is a

top or crown member 16 which substantially bridges the space between the upper portions of the end walls 14.

The bottom wall 17 of the top or crown member 16 at the transverse center thereof is provided therealong from one end to the other, the upstanding flanges 18 spaced apart a distance closely approximating the thickness of the partition plate 4 to snugly receive therebetween the upper marginal portion of the plate 4. The upper or top margins of the flanges 18 are connected therealong by the integral cap strip 19 which contacts from above the top edge face of the plate 4.

The space between the flanges 18 at their junction with the bottom wall 17 is open to provide a slot 20 so that the top or crown member may be readily placed in position and effectively supported by the partition plate 4.

Associated with each of the trays T is an upwardly and inwardly swinging lid 21, the inner longitudinal margin of which having disposed therealong, a depending flange 22 which extends into the top or crown member 16 and has close contact with the inner face of a side wall 23 of the top or crown member 16 when the lid 21 is in closed position. The lid 21 when in closed position rests upon the edges *a* of the end walls 14 and the outer longitudinal margin of the lid carries a depending flange 24 which overlies the upper marginal portions of the outer side wall 12 of a tray. The end margins of the lid 21 are provided with the depending flanges 25 which overlie the top marginal portions of the end walls 14.

Rigidly held to the inner face of each of the flanges 22 is a leaf 26 of a hinge H, the coacting leaf 27 being rigidly held to the bottom wall 17 of the top or crown member 16.

Hingedly connected, as at 28, to each of the lids 21 at substantially the longitudinal centers thereof, is an end portion of a hasp member H of a length to extend outwardly beyond the adjacent outer side wall 12 of a tray T. The outer portion 29 of the hasp H is inwardly or downwardly disposed and is of substantially V-form with the apex outwardly disposed. This portion 29 is of such dimensions to bridge an outwardly directed drip ledge 30 which extends along each outer side wall 12 of a tray T and continues across the end walls 14 of the trays.

The outer extremity of the portion 29 of one of the hasp members 29 is continued by a foot 31 which lies flat against an outer side wall 17 when the hasp is in locking position. This foot 31 is provided with an opening 32 for registry with an opening 33 in the adjacent closure member of plate 7 and through which registering opening is adapted to be inserted an end portion of a locking bar 34.

The locking bar 34 is slidably disposed through the guide loops 35 depending from the bottom walls 36 of the trays T preferably in close proximity to the outer side walls 17 of the trays T. The bar 34 is of a length to extend not only through and beyond the registering openings 32 and 33 but also through and beyond the opening 37 in the second closure member or plate 7.

The end portion of the bar 34 which extends outwardly beyond the foot 31 is provided with an opening 38 through which is insertible the shackle 39 of a conventional type of lock 40. The opposite end portion of the bar 34 which extends out through the opening 37 is provided with a T slot 41 with the head *b* inwardly disposed and

the stem *c* thereof being herein shown of a width greater than the width of the head *b* of the slot 41. The bar 34 is flat and of a width to allow for the slot 41.

The extremity of the portion 29 of the second hasp H or the hasp at the same side of the chest as the opening 41, is continued by a shank 42 of a width slightly less than the width of the stem *c* of the slot 41. The outer extremity of the shank 42 is provided with a cross member 43 of a length slightly less than the length of the head *b* of the slot 41 so that said member 43 may be readily inserted from above through the head *b* of the said slot 41.

The bar 34 is applied after the closure members or plates 7 have been swung upwardly and inwardly into closed position. The head 43 is first inserted from above through the head *b* of the slot 41 whereby endwise movement is given the bar 34 to bring the shank 42 into the stem *c* of the slot 41. This movement will place the opening 38 in the opposite end portion of the bar 34 outwardly of the adjacent closed member or plate 7 so that the applied lock will hold when desired the members or plates 7 against unauthorized opening.

From the foregoing description it is thought to be obvious that a tool chest constructed in accordance with my invention is particularly well adapted for use by reason of the convenience and facility with which it may be assembled and operated.

I claim:

1. A tool chest comprising a body having bottom, end and side walls, said side walls extending a relatively short distance only upward from the bottom wall, outwardly and downwardly opening closure members for the open side portions of the body, a pair of trays within the top portion of the body, a lid for closing the top of each of the trays, and means common to the closure members and lids for releasably holding the same in closed position.

2. A tool chest as set forth in claim 1, wherein a vertical partition divides the interior of the body and extends lengthwise thereof and above its top, the lids and the trays being positioned at opposite sides of the partition, and means extending transversely of said body to support the trays in place.

3. A tool chest as set forth in claim 1, wherein a vertical partition divides the interior of the body and extends lengthwise thereof and projects a distance above its top, a crown member mounted on the upper portion of the partition and extending therealong, said crown member also extending out from the opposite sides of the partition, means for hingedly connecting the lids to the outer portions of the crown member, locking means common to said closure members and the lids, and a hand hold formed in the center of the projecting portion of said partition.

ABE H. OLIVER.
